UNITED STATES PATENT OFFICE

2,487,999

DISPENSER WITH REMOVABLE CONTAINER

Carl C. Bauerlein, Glencoe, and Edward J. Jaskiewicz, Chicago, Ill., assignors to The Dole Valve Company, Chicago, Ill., a corporation of Illinois

Application June 20, 1945, Serial No. 600,540

5 Claims. (Cl. 222—325)

1

Our invention relates to a dispenser and more particularly to a dispenser unit which can be bodily removed from a housing without necessitating any special disconnecting operations.

In the use of dispensers and particularly those for dispensing fluids such as carbonated beverages and the like, it is important that the dispensing unit be readily accessible for purposes of repair, cleaning and the like. Frequently such a dispensing unit is located in a very cramped or limited space and as a consequence it is highly desirable that the unit be capable of being removed without necessitating the manual disconnection of parts.

Accordingly it is the aim of our invention to provide a dispensing unit which can be bodily removed from its place of use solely by an upward displacement of the unit and without necessitating any special manual disconnecting operations.

Another object of this invention is to provide a fluid dispensing unit which can be readily introduced in a housing and mounted in an operative position solely by lowering it into its intended position of use.

Another object of this invention is to provide a dispenser unit which may be bodily removed from a casing by merely displacing it from its seat in the casing.

In accordance with the general features of this invention there is provided a self-contained removable dispensing unit for disposition in a housing having a nozzle receiving opening, the unit including a fluid container, a cooling coil and a downwardly depending nozzle having associated therewith a guide member for telescoping the nozzle opening and a flange to seat on a portion of the housing defining the opening, the unit being bodily displaceable away from said flange which provides a seat for the unit whereby the guide member and the nozzle can be withdrawn away from said opening, all without necessitating any manual disconnections other than the bodily displacement of the unit.

Still another feature of the invention relates to the provision in the aforesaid unit of a connection for the coil which can be withdrawn from cooperation with a source of fluid supply solely by a displacement of the unit off of its seat.

Still another feature of the invention relates to the provision in the aforesaid unit of valve means for controlling the dispensing of fluid from the nozzle and which includes a part having a freely detachable engagement with manually operated means in the housing whereby the valve

mechanism can be disconnected from the manually operated device in the housing solely by bodily displacement of the unit from its seat in the housing.

5 Other objects and features of this invention will more fully appear from the following detailed description taken in connection with the accompanying drawings which illustrate a single embodiment thereof and in which:

10 Figure 1 is a fragmentary cross-sectional view through a dispensing housing showing our novel dispensing unit in operative position; and

15 Figure 2 is a fragmentary sectional view similar to Figure 1 showing the unit in the process of being displaced bodily from the housing.

As shown on the drawing:

20 The reference character 9 designates generally a housing which may be of any suitable construction and is provided with a removable top designated generally by the reference character 8 (Figure 1). Positioned within the housing is a removable dispenser unit designated generally by the reference character 7 which includes a fluid container 10 for accommodating a fluid, such as 25 beverage syrup, to be dispensed. In addition the unit 7 includes a cooling coil 11 disposed about the lower portion of the container 10 and which has an inlet end connection 20 to be described more fully hereinafter. Also the coil 11 has an outward connection 12 which communicates with the interior of a plunger controlled valve 13 for controlling the flow of fluid from the coil to the 30 interior of a nozzle head 14.

35 It should be noted at this time that the construction of the dispensing coil and its relation to the container are the subject of a separate invention and are being covered in the copending application, Serial No. 570,058, filed December 28, 1944. Also the construction of the nozzle head 14 and the depending nozzle 15 is the subject of a separate invention and is being covered in the copending application, Serial No. 575,782, filed February 2, 1945. Also the subject matter of the details of the valve mechanism 13 is being 40 covered in a separate copending application, Serial No. 600,780, filed June 21, 1945.

45 The nozzle head 14 has a downwardly depending circular skirt 16 for telescoping an opening 17 formed in a tubular flange structure 18 in the bottom of the housing 9. This skirt 16 constitutes a guide member and is adapted to tightly and snugly fit in the cylindrical opening of the tubular element or flange sleeve 18, with the nozzle 15 projecting beyond the housing shown 50 in Figure 1.

We also provide the skirt 16 with a resilient annular gasket 18 which may be of the flap type and is adapted to sealingly engage the inner surface of the sleeve 18 when the unit is mounted in operative position within the housing 9. From Figure 1 it is also clear that the head 14 of the nozzle structure has its undersurface arranged to seat on the flange 18' of the sleeve 18 so that the unit is firmly supported within the housing 9.

Referring to the cooling coil 11, it will be perceived that its end 20 is arranged to telescope a hole 22 in a tubular block 23 arranged at the bottom of the housing 9 for connection through a valve 24 to a suitable source of fluid such as carbonated water and the like. The valve 24 may be of any conventional construction and includes a threaded end 25 for coupling to a suitable supply conduit.

The machined end 20 of the cooling coil is adapted to have a snug fit in the hole 22 and is preferably provided with a rubber gasket 21 so as to have a seal-tight engagement with the block 23. The fit that is provided is a sliding type of fit so that upon upward movement of the unit the end 20 of the coil can be withdrawn from the block 23.

The valve mechanism 13 has projecting laterally therefrom the free end of a plunger 26 adapted to make contact with the head 27 of an operating plunger 28 suitably carried in a front wall of the housing 9. This plunger 28 is arranged to cooperate with a rotatable cam member 29 having a handle 30 for turning the same. The construction of this cam is such that upon rotation of the handle the plunger 28 will be moved inwardly to depress the plunger 26 and thus result in the operation of the dispenser unit to dispense fluid through the nozzle 15. The specific construction of the handle 30, the cam 29 and the plunger 28 associated therewith is not part of this invention since the same is being covered in a copending patent application, Serial No. 600,541, filed June 20, 1945. It should, however, be noted that the cam 29 and the handle 30 are carried on a false front 31 suitably attached to the housing 9.

It will, of course, be appreciated that any suitable mechanism can be employed for depressing the plunger 26 and that as far as this invention is concerned, the only prerequisite is that the plunger be free for quick disconnection from the mechanism without requiring any manual disconnecting operations.

Normally when the dispensing unit is in operative position the valve 24 is open so that a source of fluid or carbonated water is being supplied to the coil 11. It is, of course, to be understood that the coil 11 may be cooled by any suitable means such, for example, as ice disposed within the housing 9. When the unit is in operative position, it will be in the position shown in Figure 1 with the end 20 of the coil in a seal-tight fit in the block 23 and with the guide element or skirt 18 tightly nested in the sleeve 18. Also when in this position, the plunger 26 will be engaged by the head 27 of the mechanism for manually depressing the same. It is only upon depression of the plunger 26 that the valve 13 is opened to allow carbonated fluid to flow into the inside of the nozzle which at the same time results in the flow of syrup along with the carbonated water out of the nozzle 15. The detail mechanism for accomplishing this is not part of this invention and as far as this invention is concerned the interior mech-

anism of the nozzle may be of any suitable construction.

When it is desired to remove the unit from cooperation with the housing for the purpose of cleaning or repairing the same, the only mechanical operations that are required are to first close the valve 24 and then lift the unit 7 upwardly away from its seat on the bottom of the housing as shown in Figure 2.

10 During this movement, by reason of the quick disconnection at 20 for the end of the coil and also the lack of any fastening at either the plunger 26 or the nozzle 16, the entire unit can be completely removed without necessitating that the operator perform any mechanical disconnect operations such as unscrewing couplings, bolts and the like.

15 After the unit has been repaired or cleaned, it or a new unit may be readily placed back in the housing by merely inserting the guide skirt 16 in the sleeve 18 and aligning the end 20 of the coil with the hole 22. When the unit is completely seated on the bottom of the housing, the plunger 26 will automatically be in engagement with the head 27 of the mechanism for controlling the reciprocation of the plunger in the dispensing of fluid.

20 It will, of course, be understood that various details of construction may be varied through a wide range without departing from the principles of this invention and it is, therefore, not the purpose to limit the patent granted hereon otherwise than necessitated by the scope of the appended claims.

25 35 We claim as our invention:

1. A self-contained removable dispenser unit for disposition in a housing having a nozzle receiving opening, said unit including a fluid container, a cooling coil, an inter-engaging connection between said cooling coil and housing, a downwardly depending nozzle having associated therewith a guide member for telescoping said nozzle opening and a flange to seat on a portion of the housing defining said opening, said unit being bodily removable from said housing solely by raising it out of the housing whereby said guide member and nozzle can be withdrawn upwardly away from said opening, valve means controlling the flow of fluid from said cooling coil and container and carried by said unit, free of any connection with said housing for bodily removal with said unit, an operating handle on said housing, and an operative connection between said operating handle and said valve means, so constructed and arranged with respect to said interengaging connection and nozzle receiving opening as to have operative engagement therewith when said flange is seated on the portion of the housing defining the nozzle opening and said interengaging connection is made.

2. A self-contained removable dispenser unit for disposition in a housing having a nozzle receiving opening, said unit including a fluid container, a cooling coil, an interengaging connection between said coil and housing, a downwardly depending nozzle having associated therewith a guide member for telescoping said nozzle opening and a flange to seat on a portion of the housing defining said opening, said unit being bodily removable from said housing solely by raising it out of the housing whereby said guide member and nozzle can be withdrawn upwardly away from said opening, a valve mechanism connected with said cooling coil and container for controlling the dispensing of fluid from said cooling coil and con-

tainer through said nozzle including a depressible plunger readily displaceable with the unit from an operative position solely by the elevation of the unit in the housing, a movable operating handle on the outside of the housing and means operated thereby and so positioned with respect to said nozzle receiving opening and said interengaging connection as to have registering engagement with said plunger upon engagement of said guide member with said nozzle receiving opening and the making of said interengaging connection.

3. A self-contained removable dispensing unit for disposition in a housing having a nozzle receiving opening and control means for controlling the dispensing of fluid from the unit, said unit including a fluid container, a downwardly depending nozzle having associated therewith a guide member for tightly telescoping said nozzle opening and a flange to seat on a portion of the housing defining said opening, and a valve mechanism for controlling the flow of fluid out of the nozzle including a depressible plunger, operating means on the outside of said housing operable by said control means to depress said plunger, and so positioned as to be aligned for registering engagement therewith upon engagement of said guide member with said nozzle receiving opening and the seating of said flange on the portion of the housing defining the nozzle opening, and said plunger being readily displaceable from cooperation with said operating means in the housing solely by lifting of the unit out of the housing and away from said flange.

4. A self-contained removable dispenser unit for disposition in a housing having a nozzle receiving opening and provided with a source of fluid supply, said unit including a fluid container, a cooling coil associated therewith, a downwardly depending nozzle having in proximity thereto a guide member for tightly telescoping said nozzle unit, a flange to seat on a portion of the housing defining said opening, a connection on an end of said coil readily detachable solely upon upward movement of the unit for cooperation with said source of fluid supply, said unit being bodily removable upwardly from the housing solely by raising the same off of said flange whereby said guide member and nozzle can be withdrawn upwardly away from said opening and the connec-

tion with said fluid supply can be broken, and a valve mechanism for controlling the dispensing of fluid from said cooling coil and container through said nozzle including a depressible plunger having a free outer extremity so that the unit including said valve mechanism can be bodily lifted without necessitating any mechanical disconnection of the plunger, a movable valve operating handle on said housing, a depressible member operated thereby and so positioned as to have registering engagement with said plunger upon engagement of said guide member and said connection on the end of said cooling coil with their respective connections in said housing.

5. A self-contained removable dispensing unit for disposition in a housing having a nozzle receiving opening and control means for controlling the dispensing of fluid from the unit, said unit including a fluid container, a downwardly depending nozzle having associated therewith a guide member for tightly telescoping said nozzle opening and a flange to seat on a portion of the housing defining said opening, a fluid supply connection, arranged to supply fluid for dispensing through said nozzle, valve means on said dispensing unit arranged to dispense fluid through said nozzle, said fluid supply connection including a male member for slidingly and sealingly telescoping an opening in a fluid source of supply associated with said housing and said control means including a valve operating member on said housing so positioned with respect to said flange and said opening for said source of fluid supply as to come into operative engagement with said valve means upon the seating of said dispensing unit on said flange and the engagement of said male member with said opening.
